REFRIGERATING APPARATUS AND CABINET STRUCTURE

Lawrence A. Philipp, Detroit, Mich., assignor to
 Nash-Kelvinator Corporation, Detroit, Mich., a
 corporation of Maryland

Application April 6, 1951, Serial No. 219,592

5 Claims. (Cl. 62—117.4)

1

This invention relates generally to refrigerating apparatus and more particularly to household type refrigerators.

One of the objects of the present invention is to provide an improved arrangement with a household type of refrigerator cabinet, of a refrigerant motor-compressor unit, and a refrigerant condenser so as to increase the usable food storage space in the cabinet and at the same time maintain accessibility of the unit and condenser and retain ease of assembly of the refrigerator.

Another object of the invention resides in the provision of a household refrigerating apparatus having an improved arrangement of units thereof including a motor-compressor unit mounted on fin-like reinforcing ribs of a heat dissipating flue member on which is also mounted, a condenser coil interwinding between the fin-like reinforcing ribs.

Further objects and advantages of the present invention will be apparent from the following description, reference being had to the accompanying drawings, wherein a preferred form of the present invention is clearly shown.

In the drawings:

Fig. 1 is a front view, with parts broken away, of a household refrigerating apparatus embodying features of my invention;

Fig. 2 is a fragmentary, vertical sectional view of the refrigerator, taken along the line 2—2 of Fig. 1;

Fig. 3 is a fragmentary, horizontal sectional view of the refrigerator, taken along the line 3—3 of Fig. 2;

Fig. 4 is a broken, elevational view of a refrigerating condensing element of the refrigerator and mounting therefor, taken along the line 4—4 of Fig. 2;

Fig. 5 is a fragmentary, horizontal sectional view, similar to Fig. 3, of a modification of the invention;

Fig. 6 is a vertical sectional view of a mounting detail of the condenser element, taken along the line 6—6 of Fig. 2;

Fig. 7 is a fragmentary, horizontal sectional view of another modification of my refrigerator; and

Fig. 8 is a fragmentary elevational view of the refrigerator, taken along the line 8—8 of Fig. 7.

Referring to the drawings by characters of reference, the refrigerating apparatus shown is of the household type having a cabinet, designated generally by the numeral 20. The cabinet 20 may be constructed generally of a sheet metal casing 22, and a sheet metal liner 24 each of which is

2

preferably box-like in shape. Between the corresponding walls of the cabinet casing 22 and the liner 24, suitable heat insulation 26 of any of the well known types is preferably provided to decrease heat leakage into the cabinet. A food storage compartment 28, formed by the inner wall surface of the liner 24, preferably extends substantially from top to bottom of the cabinet so as to utilize substantially all of the available space in the cabinet for the storage of food and other things to be refrigerated. An access opening 30 in the front of the cabinet 20 may be closed by a suitable door 32 which may be hinged, as at 34, to one side wall of the cabinet.

15 Adjacent the bottom of the cabinet 20, the casing rear wall thereof is formed in part by a sheet metal panel 35 which may extend, as in the present construction, entirely across the width of the cabinet. The panel 35 is formed with a lower and inwardly offset portion 36 to provide a rear wall recess, or machinery compartment 38 for partly receiving a refrigerant motor-compressor unit 40. As is shown more clearly in Fig. 5, the recess 38 is preferably located substantially midway between the sides of the cabinet.

20 At its upper edge, the casing lower rear wall panel 35 has an inwardly offset flange 42 which engages behind the casing upper rear wall panel to be held in place thereby; the offset 42 being such as to provide a flush relationship of the upper and lower panels at the joint thereof. The lower panel 35 and the adjoining upper panel may be lap welded together at the flush joint thereof or they may be secured together in any other suitable manner. Along its lower edge, the casing rear wall panel 35 may be secured by screws or by other suitable means to an upturned rear flange 44 of the casing bottom wall, designated by the numeral 45.

25 The liner 24, in spaced relationship to and forwardly of the panel recessed wall portion 36 has a lower rear portion which is angularly disposed, as at 45, and arranged to extend upwardly and rearwardly from the cabinet bottom wall in substantially parallel relationship to an intermediate portion 46 of the recessed panel 35.

30 At the rear of the cabinet 20 is a heat dissipating refrigerant condenser member and flue forming channel member 47 which cooperates with the cabinet rear wall and recess 38 to provide a flue 48 for carrying away heat of condensation and heat generated by the motor-compressor unit 40. As shown, the flue forming channel member 47 may extend substantially entirely across the width of the cabinet and may

extend from the bottom of the cabinet partway up the back thereof.

The flue member 41 preferably has a rear wall 50 and integral, oppositely disposed side walls 52. Preferably, the flue member 41 is made of sheet metal. Outturned flanges 53, extending along the side edges of the flue member sides 52, may be secured by screws or by other suitable means to the casing 22. In the back wall 50 of the flue member 41, I provide a plurality of horizontally extending, vertically spaced ribs 54 to reinforce the wall and also to function as heat dissipating fins.

Secured to the inner surface of the flue member rear wall 50 is a refrigerant condenser coil 56, preferably of the conduit or coil type which together with the flue member constitutes a refrigerant condenser. As shown more clearly in Fig. 4, the condenser coil 56 is arranged to extend sinusously up the flue member rear wall 50 with adjacent coil runs winding between the reinforcing ribs 54 to lie flat against the inner surface of the wall. Any of the well-known suitable cements may be used to secure the condenser coil 56 to and in good heat exchange relationship with the inner surface of the flue member. One end of the condenser coil 56 is connected to the motor-compressor unit 40 and the other end of the coil 56 is in communication with a refrigerant cooling element or evaporator 60 which may be located in the upper region of the storage compartment 28. A small diameter or capillary tube 61 may connect the outlet end of the condenser coil 56 to the evaporator 60 to control flow of refrigerant thereto or any other suitable refrigerant flow control device may be used. In operation of the refrigerating apparatus, gaseous refrigerant returns to the compressor 40 from the evaporator 60 through the conventional return conduit 62 whence the refrigerant is delivered to the condenser coil 56.

Adjacent the bottom of the condenser member or flue 48, the reinforcing ribs 54 thereof are of increased width and are flattened, as shown, so that a pair of laterally spaced brackets 63 may be positioned flat against the ribs and be welded or be otherwise rigidly secured thereto. The brackets 63 include lower horizontal legs 64 which extend into the recess 38 and straddle the motor-compressor unit 40 for supporting the same. As shown more clearly in Fig. 6, the horizontal bracket legs 64 may be of general U-section and support resilient mountings, such as helical coil springs 66, for resiliently supporting the motor-compressor unit 40. Laterally extending supports, such as angle members 67, may be welded in oppositely disposed relationship to the side of the motor-compressor unit and these angle members 67 may have horizontal legs to seat on the upper ends of the spring mountings 66, as shown in Fig. 6.

Each of the mounting springs 66 is preferably provided with a vibration damper 68. These vibration dampeners 68 may be made of rubber in the well-known form of grommets and be secured in apertures in the angle members 67 below and coaxial with the springs 66. A bolt 70 extends through each of the rubber vibration dampeners 68 and screwthreads into the horizontal legs of the angle members 67. These bolts have a tight, bond-like fit with the rubber grommets so as to effect a vibration dampening action therewith on the spring mountings 66. Nuts 72 threaded onto the bolts may be tightened down to hold the parts rigid for shipping purposes. Access openings 13

may be provided in the flue member 41 to give access to the spring mountings and associated parts.

Seating on the springs 66, the motor-compressor unit 40 terminates at its lower end intermediate the cabinet bottom wall liner and casing bottom wall, as shown for example in Fig. 2. Immediately above the motor-compressor unit 40, the recessed cabinet panel 35 is provided with a reversing curvature, as at 74, so as to decrease resistance to upward flow of air rising from the motor-compressor unit 40 to facilitate removal of heat from the machinery compartment 38. At their bottom edges, the recessed panel 35 and the flue member 41 cooperate in forming an air inlet substantially in the plane of the casing bottom wall.

The evaporator 60 may be of any suitable well known type, such as the type which has a storage container whose walls are refrigerated by the passing of refrigerant through passages therein or through a tube or coil in good heat conducting relationship with the container walls. The front of the evaporator 60 may be closed by a suitable door 76 to decrease loss of cold air from the compartment.

In the lower region of the storage compartment 28, I have shown containers which are suitable for the storage of fresh fruits and vegetables including a pair of laterally positioned containers 78 and a relatively large storage drawer 80. The storage drawer 80 may be located immediately beneath the containers 78 at the bottom of the cabinet and may have a rear wall 82 inclined substantially parallel to and located adjacent the inclined cabinet liner wall 45 so as to occupy substantially all available storage space in the lower region of the cabinet. Supports 84, secured to the sides of the cabinet liner 24, may be provided to support slide rails 86 for the drawer 80 and the container 78 may be similarly slidably supported. Intermediate the container 78 and the evaporator 60, a number of shelves 88 may be provided and supported on button-like supports 90 which may be secured to the liner side walls by screws or by other suitable means.

Referring now to the modification shown in Fig. 5, this construction is similar to the refrigerator above described and therefore like parts are designated by like numerals. In the construction of the previously described cabinet, the liner 24, in the vicinity of the recess 38 extended in an inclined plane entirely across the width of the cabinet whereas in Fig. 5, the liner at the recess 38 is contoured as at 92 following, in general, the curvature of the recessed casing panel 34. Also, the back of the drawer 80 in the modification is formed with an inwardly directed recessed portion, as at 94, to conform with the curvature of the liner whereby I increase the usable storage capacity of the drawer.

Referring now to the modification shown in Figs. 7 and 8, the refrigerator embodying the modification is similar to those previously described and therefore like numerals have been used to designate like parts. The present refrigerator cabinet is provided at the back thereof with a panel 94 which is secured around its outer periphery to an inturned flange 96 of the cabinet casing. Adjacent the bottom of the cabinet, the panel 94 is cut out, as at 98, or is provided with a clearance opening to receive the motor-compressor unit 40. The clearance opening is closed by a panel 100 which is contoured to form an inwardly directed recess 102 for the motor-compressor unit.

The recess containing panel 100 may overlap the panel 94 and be welded or be otherwise suitably secured thereto.

From the foregoing description, it will be now understood that I have provided an improved arrangement of a refrigerator cabinet and refrigerant condensing element therefor in the interest of increasing usable storage space in refrigerator cabinets while at the same time retaining the desirable features of accessibility of the condensing element and ease of assembling same with the cabinet. It will further be understood that the flue panel 50 presents a desirable, large cooling surface for dissipating the heat of condensation and heat otherwise generated by the motor-compressor unit and that the condensing element is carried by the flue member in a manner to transfer heat efficiently thereto and so that the condensing element and flue member are readily removable as a unitary structure from the cabinet. In addition, the motor-compressor unit may be readily removed from the flue panel by merely removing the stop nuts after which the motor-compressor unit may be withdrawn from between its straddling supports. Also, the motor-compressor unit supports are secured directly to fin-like ribs on the flue member so that the supports act to conduct heat to the flue member for dissipation to atmosphere.

Although only a preferred form of the invention has been illustrated, and that form described in detail, it will be apparent to those skilled in the art that various modifications may be made therein without departing from the spirit of the invention or from the scope of the appended claims.

I claim:

1. In a refrigerator, a cabinet having a rear wall provided with an inwardly directed recess, a refrigerant compressor received within said recess, a panel overlying the cabinet rear wall forming a flue therewith and communicating with said recess, said panel having spaced horizontally extending reinforcing ribs, a refrigerant condenser coil mounted on and to the inner surface of said panel, said coil being sinuously bent and arranged to have horizontal runs respectively disposed in the spaces between said ribs, and vibration dampener mountings supporting said compressor and secured to said reinforcing ribs.

2. In a refrigerator, a cabinet wall having an inwardly directed recess, a flue forming member overlying said wall in spaced relationship to said recess, a refrigerant compressor positioned in said recess between said wall and said flue forming member, said flue forming member having a plurality of substantially horizontally extending vertically spaced reinforcing ribs, a re-

frigerant condenser coil attached to the inner surface of said flue forming member between said flue forming member and said refrigerant compressor, said refrigerant condenser coil extending sinuously between successive reinforcing ribs and being operatively connected to said compressor, a pair of brackets overlying portions of said condenser coil and secured to and flat against said reinforcing ribs, and coil springs interposed between said brackets and said compressor.

3. Refrigerating apparatus comprising, a cabinet having a machine compartment, a flue member overlying said compartment having inwardly directed corrugations, spaced bracket members secured to said inwardly directed corrugations and having portions thereof extended within said compartment, a motor-compressor unit extending into said compartment between said bracket members, supports secured to and on opposite sides of said unit respectively overlying said extended portions, and spring mountings compressed between said portions and said supports resiliently supporting said unit.

4. Refrigerating apparatus comprising, a cabinet having a machine compartment, a single-ply flue member overlying said compartment and having inwardly directed corrugations, horizontally spaced bracket means secured directly to said corrugations and having horizontal legs extending inwardly therefrom, a motor-compressor unit extending into said compartment between said horizontal legs, spring mountings on said leg supports secured to and on opposite sides of said unit resting on said spring mountings and resilient means limiting movement of said unit on said spring mountings.

5. In a refrigerator, a cabinet, a wall member spaced from a wall of said cabinet to form a flue, a refrigerant motor-compressor unit disposed between said wall member and the wall of said cabinet to be cooled by air ascending the flue, said wall member having spaced horizontally extending reinforcing ribs, a refrigerant condenser coil mounted on and to the inner surface of said wall member, said coil being sinuously bent and arranged to have horizontal runs respectively disposed in the spaces between said reinforcing ribs, and vibration dampener mountings supporting said compressor and secured to said reinforcing ribs.
